Primary Examiner — Brett Miller*Assistant Examiner* — Jessica M Gebhart(74) Attorney, Agent, or Firm — Bayramoglu Law Offices LLC(57) CLAIM

The ornamental design for a beach chair carry bag, as shown and described.

DESCRIPTION

FIG. 1 is a front perspective view of a beach chair carry bag showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top perspective view thereof;

FIG. 9 is a partially enlarged view showing an indicated portion in FIG. 1; and,

FIG. 10 is a partially enlarged view showing another indicated portion in FIG. 1.

The broken lines indicating enlarged portions of the design form no part of the claimed design.

1 Claim, 8 Drawing Sheets(56)
